UNITED STATES PATENT OFFICE.

JOHN SCHIES, OF ANDERSON, INDIANA.

DESIGN FOR A JAR.

SPECIFICATION forming part of Design No. 29,032, dated July 12, 1898.

Application filed February 18, 1898. Serial No. 670,868. Term of patent 14 years.

To all whom it may concern:

Be it known that I, JOHN SCHIES, a citizen of the United States, residing at Anderson, in the county of Madison and State of Indiana, 5 have invented and produced a new and original Design for Jars, of which the following is a specification, reference being had to the accompanying drawings, forming part thereof.

Figure 1 is a vertical longitudinal section, 10 and Fig. 2 is a side view, of a jar, showing my new design.

As shown in the drawings, the leading or material feature of my design for a jar consists in the sectional configuration of the mouth of 15 the jar, as best shown in Fig. 1, with the external outward flare at A in an upward direc-

tion and with the inner flared portion B uniting at C with the rounded inner surface D.

The jar has its body formed with plane panels E and slopes thence into union with the 20 cylindrical neck F, which is ornamented about midway between the panels E and flare A with the annular bead G.

Having thus described my invention, what I claim as new is—

The design for a jar as herein shown and described.

JOHN SCHIES.
